Letters Patent No 1673. Dated Novr 11. 1862.

The schedule referred to in these Letters Patent and making part of the same.

To all whom it may concern

Be it known that I, Elmer J. Noy, of Lowell, in the County of Middlesex and State of Massachusetts, have originated and designed a new Pattern for Carpets or other fabrics, of which the following is a full, clear and exact description, reference being had to the accompanying drawings making part of this Specification,

A is a large set figure composed principally of leaves of various sizes, B. is a large long figure, with scroll outline, composed of a rosette 1. mottled work 2. enclosed by a solid frame, and the diamond ground work 3. Surrounding fig. B. are the dotted leaves, 4.

C. and D. at the sides when matched form a group of various sizes blocks enclosed by a frame of scrolls.

E. is an eight pointed frame enclosing small leaves and flowers. Fig. C. and D. are connected with figs. A. and B. respectively by the bars 5. 6. and 7. 8.

Sections of figures similar to E. are shown at the sides and lower end of the design.

In the lower corners are sections of figures, similar to that formed by matching C. and D.

The remainder of the design is composed of a ground of small regular work.

The colors employed for the different portions of the design, may be varied to suit the taste and wish of the manufacturer.
